UNITED STATES PATENT OFFICE.

NORMAN L. STEVENS, OF BLOOMFIELD, NEW JERSEY.

DESIGN FOR A CLOCK CASE.

Application filed June 29, 1928. Serial No. 27,314. Term of patent 14 years.

To all whom it may concern:

Be it known that I, NORMAN L. STEVENS, a citizen of the United States, and resident of Bloomfield, county of Essex, State of New Jersey, have invented a new, original, and ornamental Design for a Clock Case, of which the following is a specification, reference being had to the accompanying drawing, forming part thereof.

In the accompanying drawing:

The figure is a perspective view of a clock case showing my new design, the dominant feature being the particular type of ornamentation as shown near the border of the base and around the marginal face flange above the base.

I claim:

The ornamental design for a clock case, as shown and described.

NORMAN L. STEVENS.
